INSULATION

Campbell D. Cope, St. Louis, Mo.

Application March 20, 1939, Serial No. 263,090

3 Claims.

(Cl. 20—4)

This invention relates to insulation and this application is a continuation-in-part of my application Serial No. 53,515, filed Dec. 9, 1935.

Objects of the invention are to produce a highly efficient and relatively inexpensive insulation of loose fireproof character that may be poured or caused to flow into confined and inaccessible spaces without the necessity of providing skilled workmen; to provide such an insulation composed of a mass of unattached, non-inflammable sections of different lengths, some of which are of substantial length and arcuate in cross-section, and others comparatively short and flat in cross-section, the mass also including numerous non-inflammable tubular sections of substantial length unshredded, uncrushed, and unbroken, the length of many of said sections being such that they will engage the adjacent surfaces of spaced wall portions and partially support the mass of insulation and prevent it from becoming matted, etc.; and to provide an insulation comprising a large proportion of split tubes of different lengths, and means for sustaining the mass of insulation so that it will not become packed or compressed when placed in position for use.

Another object of the invention is to provide an improved insulation composed of straw or other analogous vegetable matter having a large proportion thereof split and cut into comparatively short lengths which are arcuate in cross-section and having another substantial proportion thereof of tubular form long enough to span between and engage the adjacent surfaces of spaced wall portions forming the walls of frame buildings, and other buildings having spaces in the walls thereof.

Other objects and advantages of the invention should be readily apparent from the following description, reference being made to the annexed drawing, in which—

Fig. 1 is a perspective view showing a wall section having my improved insulation therein.

Fig. 2 is a vertical cross-sectional view of the wall.

As shown in the annexed drawing, the outer wall 1 is separated from the laths or parts 2 which may be coated with and support the plaster 3. The plaster 3 has integral portions 4 extending through the spaces between the laths and forming shoulders in the space between the inner and outer walls. This space is filled with my improved insulation which is made of straw or analogous material. The straw or analogous material is cut or broken or otherwise processed

5 to form a mass of sections 5 obtained by splitting the straw longitudinally and breaking or cutting them into relatively short lengths. A considerable proportion of the sections 5 are arcuate in cross-section and, therefore, will cooperate with the remaining smaller flat sections to form a cellular insulation.

10 My improved insulation also contains a large number of tubular sections 6 which are unattached, unbroken and uncrushed, and are non-inflammable, as is the mass 5. The tubular sections 6 are long enough to span and extend across between the outer wall 1 and to engage their ends upon the protruding portions 4 of the plaster, and some of said sections may extend 15 within the spaces 7 between the boards of the outer wall 1. Thus, these tubular sections 6 are supported and sustained by the opposite wall portions included in the completed wall. The tubular sections 6 are resilient, so that they may bend considerably without breaking or becoming unduly weakened. Consequently, since the insulation includes a relatively considerable number of these supporting tubular sections at different vertical heights within the wall, all of said sections 20 that are engaged with opposite portions of the wall, or with each other, will cooperate to support and sustain the insulation in loose cellular form appropriate for the attainment of best effects and results. The two wall portions shown which are separated by an intervening space filled by the insulation represent portions of a building wall such as a residence or other building provided with the finished inner plaster surface 3. 25 The tubular sections 6 which are thoroughly mixed with the mass 5 extend in various directions in the mass, as shown. Some of these tubular sections 6 span and extend across the space between the inner and outer walls and engage the 30 opposite wall surfaces while other tubular sections 6 extend in different directions in the mass. 35

40 After the mixture or mass of material is cut and processed to proper size and lengths as explained, it is immersed in a solution to render the material non-inflammable and characterize it as a vermiculite. For such purposes, I have used Epsom salts and sodium fluoride, and I have also used other solutions optionally to sterilize and render the material antiseptic and to extend its durability and lasting qualities. Boric acid may be satisfactorily used as a fire-proofing and antiseptic agent.

45 After the material has been formed and processed in this manner, it may be dried by mechanical methods comprising the step of agitating

or stirring the material during the drying process and thereby avoiding moulding or souring. However, the material is not processed nor agitated with such force as to destroy crystallization of the chemicals or diminish the non-inflammability of the material, nor to destroy the cross-sectional arcuate form of the smaller pieces nor the tubular form of the parts 6.

After the material has been prepared in this way, it may be formed into bales or placed in packages or bags to facilitate handling and transporting, and minimizes installation costs. But it should not be compressed to such an extent as to destroy the cross-sectional arcuate or tubular forms of the different parts of the insulation. 10

The finished material may be poured or blown into the wall spaces. It is not of an adhesive character, but will easily flow and pass around the obstruction, such as headers, bridging, and other strengthening wall parts customarily used, and will fill the spaces with approximately uniform density. Being of light weight and of cellular form, and some of the parts being of tubular form to support other portions of the insulation, the material does not settle heavily and thus 20 destroy or minimize its efficiency.

This material possesses many advantages over board or quilted forms of insulation which cannot be inserted into and made to fill the wall spaces of completed buildings satisfactorily. The processing of the material increases its stiffness, leaving it resilient, and making it less subject to breakage under pressure. 30

This material may be provided and installed at comparatively very low cost and without any high degree of skill in the installation. The 35

composite insulation may be varied within the scope of equivalent limits without departure from the nature and principle of the invention.

I claim:

5 1. A cellular insulation for buildings having inner and outer walls separated by an intervening space, comprising a mass of unattached substantially non-inflammable split tubular sections of straw that are arcuate in cross-section and are resilient and are of different lengths less than the distance between said walls.

2. A cellular insulation for buildings having inner and outer walls separated by an intervening space, comprising a mass of split tubular sections that are arcuate in cross-section and of varying lengths less than the distance between said walls and of varying widths, and a relatively large number of tubular sections having a length to span and extend across said space between said walls and thereby engage opposite wall surfaces and partially support said first named sections.

3. A cellular insulation for buildings having inner and outer walls separated by an intervening space composed of a mass of unattached non-inflammable sections of different lengths less than the distance between said walls and that are arcuate in cross-section and resilient, and a relatively large number of tubular non-inflammable sections mixed with said mass and having a length sufficient to extend across said space and engage facing wall surfaces enclosing said space in which the insulation is mounted and be supported by said surfaces, and to prevent compacting and matting of said first named sections. 25

CAMPBELL D. COPE.
